UNITED STATES PATENT OFFICE.

CHARLES H. ALLEN, OF ATTLEBOROUGH, MASSACHUSETTS, ASSIGNOR TO
THE CHARLES H. ALLEN & COMPANY, OF SAME PLACE.

CUFF-BUTTON.

SPECIFICATION forming part of Letters Patent No. 645,307, dated March 13, 1900.

Application filed December 13, 1899. Serial No. 740,165. (No model.)

To all whom it may concern:

Be it known that I, CHARLES H. ALLEN, a citizen of the United States, residing at Attleborough, in the county of Bristol and State of Massachusetts, have invented a new and useful Improvement in Cuff-Buttons, of which the following is a specification.

This invention has reference to an improvement in buttons used to secure the cuffs of shirts.

In the class of cuff-buttons in which two heads are rigidly secured to the opposite ends of a bar the heads are liable to move on the cuffs and mar the surfaces of the same.

The object of this invention is to secure a firmer hold of the cuff-buttons in the buttonholes.

The invention consists in the peculiar and novel construction whereby the connecting-link secured to the center of the heads extends in the buttonhole nearly to the edges of the heads, as will be more fully set forth hereinafter.

Figure 1 is a side view of a cuff-button the heads of which are secured obliquely to my improved connecting-link. Fig. 2 is an edge view of the same. Fig. 3 is a view of the inside of one of the heads, showing the connecting-link partly in section. Fig. 4 is a sectional view of my improved cuff-button and the cuff, showing the relative positions of the same.

In the drawings, *aa* indicate the cuffs; *a'a'*, the buttonholes in the cuffs; *bb*, the heads, which are preferably placed obliquely to each other, so as to bear on the outside surfaces of the cuffs; *c*, the connecting-link, formed, preferably, of flat sheet metal; *c'c'*, extensions on the opposite ends of the link, and *c²c²* posts extending beyond the ends *c³* of the link. The posts *c²c²* are secured usually by solder to the inner surfaces of the heads *bb* at or about the center of the same.

The bar forming the link *c* is preferably

curved, as shown in the drawings. The forward edge of the link *c* is within the forward edge *b'b'* of the head, so that when in place the forward edge of the head may cover the end of the buttonhole. The inclined ends *c³c³* of the link are on a line with the annular edges of the inner sides of the heads. The extensions *c'c'* project through the buttonholes and have curved edges connecting with the rear edge of the link-bar.

The flat link *c*, with the extensions *c'c'* extending through the buttonholes, serves to support the heads and hold them against moving in the cuffs, while the posts *c²c²*, secured centrally to the heads, resist the strain on the heads and prevent the same from spreading outward, which they are liable to do when the link-bar is secured near the forward ends of the heads, as heretofore constructed.

Having thus described my invention, I claim as new and desire to secure by Letters Patent—

1. In a cuff-button, the combination with the heads, of a flat link-bar extending from near the forward end of one head to near the forward end of the other head and provided with an extension having a post centrally secured to the heads, whereby the strain on the heads is resisted by the centrally-secured link, as described.

2. In a cuff-button, the combination with the heads *bb*, of the link *c*, the extensions *c'c'* on the ends of the link, and the projecting posts *c²c²* on the extensions; whereby the obliquely-placed heads are secured together at or near their center, as described.

In testimony whereof I have signed my name to this specification in the presence of two subscribing witnesses.

CHARLES H. ALLEN.
